VALVE FOR ROCK DRILLS

Albert R. Mack, Phillipsburg, N. J., assignor to
Ingersoll-Rand Company, New York, N. Y., a
corporation of New Jersey

Application December 6, 1939, Serial No. 307,727

7 Claims. (Cl. 121—18)

This invention relates to rock drills, and more particularly to a valve mechanism for effecting the distribution of pressure fluid to the percussive element of rock drills.

One object of the invention is to obtain a light weight valve mechanism of simplified construction capable of effecting a rapid distribution of pressure fluid and a consequent rapid action of the percussive element of the rock drill.

Other objects will be in part obvious and in part pointed out hereinafter.

In the drawings accompanying this specification and in which similar reference numerals refer to similar parts,

Figure 1 is a longitudinal view, partly broken away, of one form which the invention may assume in practice and showing the valve and piston elements in limiting positions.

Figure 2 is a view similar to Figure 1 showing the valve and piston elements in other limiting positions, and

Figure 3 is a view similar to Figure 1 showing a modified form of the invention.

Referring more particularly to the drawings, 20 designates, in general, a rock drill comprising a cylinder 21 having a piston chamber 22 to accommodate a hammer piston 23 which is reciprocable in the piston chamber 22 and controls a free exhaust port 24 for the piston chamber.

The front end of the piston chamber 22 is closed by a plate 25 having a bore 26 to serve as a guide for an extension 27 of the hammer piston 23. The opposite end of the cylinder 21 is closed by a back head 28, and in the portion of the cylinder lying between the back head of the piston chamber 22 is an enlarged bore 29 to accommodate valve and rotation mechanisms designated 30 and 31, respectively.

The valve mechanism lies immediately adjacent the rear end of the piston chamber 22 and the space of the bore 29 rearwardly of the valve mechanism contains the rotation mechanism which comprises the usual ratchet ring 32 wherein is arranged the head 33 of a rifle bar 34 extending through the valve mechanism and into fluted engagement with the piston 23 in a well understood manner. The head 33 of the rifle bar may be provided with a pawl or pawls 35 for engagement with the teeth 36 of the ratchet ring for holding the rifle bar stationary during a stroke of the piston 23 to cause a partial revolution thereof.

The back head 28 may be clamped to the cylinder 21 in any well known manner and, as is cus-

tomary, serves as a housing for a rotary throttle valve 37 having a central chamber 38 which may be in constant communication with a source of pressure fluid supply, and in the wall of the throttle valve is a port 39 to afford communication between the chamber 38 and a passage 40 in the back head leading to a supply reservoir 41 in the forward end of the back head.

The valve mechanism, constructed in accordance with the practice of the invention, comprises a valve chest 42 consisting of an outer ring member 43 and a plug 44 extending through the ring member 43 and being recessed to provide an annular valve chamber 45 around the plug 44. The plug 44 carries a flange 46 at its rear end to serve as a seat for the ratchet ring 32 and the rifle bar head 33 and seats upon the rear end of the ring member 43.

The forward end of the plug terminates at the rear end of the piston chamber 22 and may be press-fitted, or otherwise secured, to an annular plate 47 encircling the plug 44 and cooperating therewith to form a closure for the rearward end of the piston chamber. The plate 47 serves, moreover, as a seat for the front end of the ring member 43 and is provided with a series of inlet ports 48 that afford communication between the rear end of the piston chamber 22 and an annular groove 49 in the rearward end of the annular plate 47 and opening into the front end of the valve chamber 45. Preferably, the inlet ports 48 are so located that their inner portions lie in the same longitudinal plane as the outer portion of the valve chamber 45.

Encircling the rearward end of the valve chamber 45, into which it opens, is an annular groove 50 from which leads an inlet passage 51 to the front end of the piston chamber.

In the form of the invention illustrated, the pressure fluid is conveyed to the valve chamber 45 by supply passages 52 leading from the supply reservoir 41 through the ratchet ring 32, the flange 46 and into the plug 44. Communication is afforded between the supply passages 52 and the valve chamber by two groups of ports 53 and 54 which are arranged in circular fashion and spaced along the length of the portions of the supply passages 52 lying in the transverse plane of the valve chamber.

The ports 53 and 54 are inclined with respect to the axis of the rock drill. Those designated 53, are inclined towards the rearward extremity of the valve chamber and the ports 54, on the other hand, are inclined towards the front end 55.

of the valve chamber 45. Annular grooves 55 are preferably formed in the periphery of the plug 44. The grooves 55 communicate with the outlet ends of the ports 53 and 54 and extend to the ends of the valve chamber so clearances will exist between the plug 44 and the inner end surfaces of the valve in all positions of the valve.

The element serving to effect the distribution of pressure fluid from the supply passages 52 to the inlet passages 48 and 51 is in the form of a ring-shaped valve 56 reciprocable in the valve chamber 45 and having, in the present instance, a smooth unbroken outer surface 51 slideable on a similar surface 58 in the ring member 43. The valve is additionally guided by an internal surface 59 on its inner surface slideable on the peripheral portion 60 of the plug 44 lying between the outlet ends of the ports 53 and 54.

In the inner surface of the valve 56 are a pair of annular grooves 61 and 62 which are in constant communication with the ports 53 and 54, respectively. The inner ends of the grooves 61 and 62 are bounded by the raised portion of the valve carrying the guiding surface 59, and at the outer ends of the grooves are shoulders 63 which are so located that the pressure fluid issuing from the ports 53 and 54 will impinge thereagainst and serve to throw the valve 56 to its limiting positions.

These limiting positions are determined by valve seats 64 and 65 located respectively at the rearward and front ends of the valve chamber 45. The valve seat 64 is of less width than the adjacent portion or end of the valve so that the outer portion of the rear end of the valve will also be constantly exposed to whatever pressure may exist in the front end of the piston chamber 22.

The entire rearward end of the valve constitutes a holding area 66 which is exposed to the pressure fluid flowing from the supply passages across the rearward end of the valve to the inlet passage 51 for holding the valve forwardly during the charging of the front end of the piston chamber. Similarly, the front end of the valve serves as a holding area 67 against which pressure fluid flowing to the rear end of the piston chamber acts for holding the valve 56 rearwardly against the seat 64 during the charging of the rear end of the piston chamber.

The operation of the device is as follows: With the valve 56 and the piston 23 in the rear-most limiting positions, as illustrated in Figure 1, pressure fluid flows from the ports 54 into the groove 62 and the adjacent groove 55, thence across the holding area 67 through the groove 49 and the inlet ports 48 into the rear end of the piston chamber to drive the piston 23 forwardly on its working stroke. During this movement of the piston, and after the exhaust port 24 has been closed thereby, the air in the front end of the piston chamber 22 will be compressed and will flow through the inlet passage 51 into the annular groove 50 against the outer portion of the rear end of the valve 56, and when the piston 23 uncovers the exhaust port 24 the pressure in the rear end of the piston chamber will drop as will also that acting against the front holding surface 67 of the valve. The compression then acting against the rear end of the valve together with the pressure fluid issuing from the ports 54 against the front shoulder 63 will immediately throw the valve forwardly against the seating surface 65 and cut off

the admission of pressure fluid to the rear end of the piston chamber.

In the new position of the valve, pressure fluid flows from the ports 53 into the groove 61 and the adjacent groove 55, thence across the holding surface 66 and through the inlet port 51 to the front end of the piston chamber for returning the piston 23. After the piston again covers the exhaust port 24 the air in the rear end of the piston chamber will be compressed and act against the exposed portions of the holding surface 67 lying in the longitudinal planes of the inlet ports 48. The valve 56 will remain in the foremost limiting position until the front end of the piston uncovers the exhaust port 24 at which time there will be an abrupt drop in pressure in the front end of the piston chamber and rearwardly of the holding surface 66. The compression acting against the front end of the valve and the force of the pressure fluid streams striking the rear shoulders 63 will then again shift the valve rearwardly to its initial position.

In the form of the invention illustrated in Figure 3, the valve designated 70 is provided at the forward and rearward ends of its inner surface with groups of annular shoulders 71 and 72, and in the plug 44 are front and rear annular slots 73 and 74 which are inclined, respectively, toward the front and rear ends of the valve chamber 45. The innermost portions of the slots 73 and 74 communicate with the supply passages 52 and the outermost portions of the slots communicate with the annular grooves 55 in the periphery of the plug 44 so that there is a constant flow of pressure fluid from supply 30 into the grooves 55 and, therefore, against the shoulders 72.

The operation of this form of the invention is similar to that of the previously described form of the valve but differs only therefrom in the respect that during the movement of the valve the shoulders 71 and 72 move successively into direct line with the pressure fluid streams issuing from the slots 73 and 74 to assure a positive and forceful movement of the valve.

I claim:

1. In a fluid actuated rock drill, the combination of a casing having a piston chamber and a piston therein, an exhaust port for the piston chamber, a valve chest comprising inner and outer members defining an annular space therebetween forming a valve chamber, inlet passages leading from the valve chamber to the piston chamber, a valve in the valve chamber to control the distribution of pressure fluid to the inlet passages and having internal surfaces to cooperate with one of the members to define channels for conveying pressure fluid to the inlet passages, passages in one of the members for introducing pressure fluid from supply into the channels, and shoulders on the valve subjected to the pressure fluid issuing from the last mentioned passages for throwing the valve.

2. In a fluid actuated rock drill, the combination of a casing having a piston chamber and a piston therein, an exhaust port for the piston chamber, a valve chest having an annular valve chamber, inlet passages leading from the valve chamber to the piston chamber, a valve in the valve chamber having internal annular grooves for conveying pressure fluid to the inlet passages, passages in the valve chest opening into the annular grooves, and shoulders on the valve subjected to the pressure fluid issuing from the last mentioned passages for throwing the valve.

3. In a fluid actuated rock drill, the combination of a casing having a piston chamber and a piston therein, an exhaust port for the piston chamber, a valve chest having an annular valve chamber, inlet passages leading from the valve chamber to the piston chamber, a valve in the valve chamber having internal annular grooves for conveying pressure fluid to the inlet passages, passages in the valve chest affording constant communication between the annular grooves and pressure fluid supply, and shoulders on the valve subjected to pressure fluid issuing from the last mentioned passages for throwing the valve.
- 5 4. In a fluid actuated rock drill, the combination of a casing having a piston chamber and a piston therein, an exhaust port for the piston chamber, a valve chest having an annular valve chamber, inlet passages leading from the valve chamber to the piston chamber, a valve in the valve chamber having internal annular grooves for conveying pressure fluid to the inlet passages, passages in the valve chest opening into the annular grooves, shoulders on the valve forming bounding surfaces for the annular grooves and being subjected to the pressure fluid issuing from the last mentioned passages for throwing the valve, and holding surfaces on the valve subjected to the pressure fluid flowing to the inlet 10 passages for holding the valve in the limiting positions.
- 15 5. In a fluid actuated rock drill, the combination of a casing having a piston chamber and a piston therein, an exhaust port for the piston chamber, a valve chest having an annular valve chamber, inlet passages leading from the valve chamber to the piston chamber, a valve in the valve chamber cooperating with the valve chest to define annular channels within the valve for 20 conveying pressure fluid to the inlet passages, passages in the valve chest inclined toward the extremities of the valve chamber for conveying pressure fluid from supply to the annular channels, and shoulders on the valve subjected to the pressure fluid issuing from the last mentioned passages for throwing the valve.
- 25 6. In a fluid actuated rock drill, the combination of a casing having a piston chamber and a piston therein, an exhaust port for the piston chamber, a valve chest having an annular valve chamber, inlet passages leading from the valve chamber to the piston chamber, a valve in the valve chamber having annular grooves in its inner surface for conveying pressure fluid to the inlet passages, supply passages in the valve chest 15 opening into the annular grooves and being inclined toward the extremities of the valve chamber, and shoulders on the inner surface of the valve subjected to the pressure fluid issuing from the supply passages for throwing the valve.
- 30 7. In a fluid actuated rock drill, the combination of a casing having a piston chamber and a piston therein, an exhaust port for the piston chamber, a valve chest having an annular valve chamber, inlet passages leading from the valve chamber to the piston chamber, a valve in the valve chamber having annular grooves in its inner surface for conveying pressure fluid to the inlet passages, supply passages in the valve chest opening into the annular grooves, shoulders on 20 the valve subjected to the pressure fluid issuing from the supply passages for throwing the valve, surfaces on the ends of the valve subjected to the pressure fluid flowing to the inlet passages for holding the valve in the limiting positions, 35 and portions of the said surfaces subjected to compression from the piston chamber to assist in throwing the valve.

ALBERT R. MACK. 40
